Primary Examiner — Selina Sikder(74) *Attorney, Agent, or Firm* — Akona IP(57) **CLAIM**

The ornamental design for a mobility remote, as shown and described.

DESCRIPTION

FIG. 1 is a front perspective view illustrating the mobility remote;

FIG. 2 is a front view illustrating the mobility remote;

FIG. 3 is a back view illustrating the mobility remote;

FIG. 4 is a side view illustrating the mobility remote;

FIG. 5 is another side view illustrating the mobility remote;

FIG. 6 is a top view illustrating the mobility remote;

FIG. 7 is a bottom view illustrating the mobility remote; and,

FIG. 8 is a back perspective view illustrating the mobility remote.

The broken lines immediately adjacent to the shaded rear surface shown in FIGS. 3 and 8 define boundaries of the claim and form no part of the claimed design. The broken lines depicting a cable in FIGS. 1-5 and 7-8 show environmental structure and form no part of the claimed design.

1 Claim, 5 Drawing Sheets(56)
